UNITED STATES PATENT OFFICE.

ANDREW EKMAN, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

LATCH.

Application filed March 7, 1927. Serial No. 173,348.

The present invention relates to latches for the doors of refrigerators and the like; and its object is to provide a latch having improved means for yieldingly holding the 5 latching bolt in certain positions, and in certain movements of the bolt urging the same into another of its positions; and further, to provide a latch having such means and adapted to be mounted on a door closure 10 swingably mounted at either of its opposite sides; and further, to provide such a latch whose parts may be readily assembled; and further, to provide such a latch having few parts and which may be easily and economically constructed.

These and any other objects hereinafter appearing are attained by, and the invention finds preferable embodiment in, the structure hereinafter particularly described 20 in the body of this specification and illustrated by the accompanying drawings, in which:—

Figure 1 is a front view of a latch and its keeper element mounted on a door closure 25 and frame or jamb thereof, respectively;

Figure 2 is a left-hand side view thereof, the door closure being partially open;

Figure 3 is an inner side view of the latch;

Figure 4 is a view in perspective of the 30 latch's casing, showing its inner side; and

Figure 5 is a view in perspective of the bolt's actuating spring.

In the embodiment of the invention illustrated by the accompanying drawings, a 35 latch is shown mounted on the closure member 1 of a door, its keeper element 2 being mounted on the jamb or frame member 3 of the door. In Figures 1 and 2 the latch is shown mounted on a closure member hinged 40 at its right-hand side, but the same latch may be mounted on a closure member hinged at its opposite or left-hand side. This latch comprises a latching bolt 4 swingably carried in a casing 6, a portion 7 of the bolt extending 45 through a slot 8 in one side wall 9 of the casing and being adapted to latchingly engage in the keeper recess 10 of the element 2 to hold the closure member 1 shut. This latching bolt may be swung by hand by any 50 suitable means or part thereof; in the illustrated construction however, it is swung by grasping its handle portion or arm 11 extending through a slot 12 in the casing's opposite side wall 13.

In the illustrated latch, the bolt 4 has portions 14, 15 spaced apart in the bolt's transverse direction. This latching bolt is a "floating" element swingably movable in the slots 8 and 12. These portions 14, 15 are adapted to abut on the inner surface of the side wall 13 of the casing adjacent the ends of the slot 12, in the latching position of the bolt as seen in Figures 1 and 3; but, when the outer portion 7 of the bolt is moved upwardly from such latching position, the portion 14 of the bolt turns on said surface while the other portion 15 moves away from said surface; and in case the latch is mounted on a door closure hinged at its opposite or left-hand side, the swinging of the 70 bolt in the opposite direction to retracted position causes the bolt's portion 15 to turn on said surface and the bolt's portion 14 to move away from said surface.

Means are provided for yieldingly holding the bolt 4 in any of its positions, and at a point in its movement toward any of its positions urging the same to that position. Such means shown is a spring 20 comprising parallel portions 21, 21 on the opposite 80 sides respectively of the bolt, this spring being mounted at its ends 22, 22 on the side wall 9 of the casing, and said parallel portions being connected by a bight portion 25 which straddles and operatively engages the 85 bolt, being seated in its notch or recess 26. Each of said parallel portions 21 comprises, in the shown construction, parallelly disposed parts 27, 28 connected by a bend 29. The parts may be assembled by thrusting the 90 handle portion 11 of the bolt endwise, first through the longer slot 8 in the casing's side wall 9 and then through the shorter slot 12 in the casing's side wall 13. The bolt's portions 14, 15 may thus be passed through the longer slot 8, but extend transversely of the bolt too far to pass through the shorter slot 12. The bight portion 25 of the spring 20 is now inserted into the bolt's notch 26, and thus, pressing the bolt's portions 14, 15, toward the side wall 13, holds the parts in assembled position.

The invention being intended to be pointed out in the claims, is not to be limited to or by details of construction of the particular embodiment thereof illustrated by the accompanying drawings or hereinbefore described.

I claim:—

1. In combination with a keeper therefor, a latch comprising: a casing having opposite side walls with slots therethrough respectively; a bolt swingable to latching position and to retracted position and having a handle portion insertable endwise through the slots in assembling the parts and a pair of portions spaced apart in the bolt's transverse direction adapted to be passed through one of the slots in such assembling, one of said pair of portions turning on the inner surface of one of casing's side walls adjacent the other slot in the bolt's swinging movement; a spring pressing the bolt to yieldingly hold the same in latching position and at a point in the bolt's movement toward either one of its said positions urging the same to that position and urging 20 one of said pair of portions into turning engagement with said surface in the bolt's swinging movement.

2. In combination with a keeper therefor, a latch comprising: a casing having opposite side walls with slots therethrough respectively; a bolt swingable to latching position and in opposite directions therefrom to retracted positions and having a handle portion insertable endwise through the slots 25 in assembling the parts and a pair of portions spaced apart in the bolt's transverse direction adapted to be passed through one of the slots in such assembling, one of said pair of portions turning on the inner surface of one of the casing's side walls adjacent the other slot in the bolt's movement to and from one of its retracted positions and the other of said pair of portions turning on 30 said surface in the bolt's movement to and from the other of its retracted positions; a spring pressing the bolt to yieldingly hold the same in latching position and at a point in the bolt's movement toward any of its 35 said positions urging the same to that position and urging one of said pair of portions

into turning engagement with said surface in the bolt's swinging movement.

3. In combination with a keeper therefor, a latch comprising: a bolt swingable to latching position and to retracted position; a spring urging the bolt to one of its said 50 positions and comprising portions on the opposite sides respectively of the bolt, said spring being mounted at its ends and its said portions being connected by a bight portion 55 operatively engaging the bolt.

4. In combination with a keeper therefor, a latch comprising: a bolt swingable to latching position and to retracted position; a spring urging the bolt to one of its said 60 positions and comprising parallel portions on the opposite sides respectively of the bolt, said spring being mounted at its ends and its said portions being connected by a bight portion 65 operatively engaging the bolt and each of its said parallel portions comprising parallelly disposed parts.

5. In combination with a keeper therefor, a latch comprising: a bolt swingable to latching position and to retracted position; a spring urging the bolt to one of its said 70 positions and comprising portions on the opposite sides respectively of the bolt, said spring being mounted at its end and its said portions being connected by a bight portion 75 operatively engaging the bolt.

6. In combination with a keeper therefor, a latch comprising: a bolt swingable to latching position and to retracted position and having a notch adapted to receive the 80 hereinafter-mentioned bight portion; a spring urging the bolt to one of its said positions, extending at one side of the bolt, having a bight portion operatively engaging in 85 said notch and being mounted at its end.

In testimony whereof I have hereunto set my hand at Grand Rapids, Michigan, this 3rd day of March, 1927.

ANDREW EKMAN.
